US00D883144S

(12) **United States Design Patent** (10) **Patent No.:** **US D883,144 S**
(45) **Date of Patent:** **** May 5, 2020**

(54) **VEHICLE BODY AND/OR REPLICA**

(71) Applicant: **HONDA MOTOR CO., LTD.**, Tokyo (JP)

(72) Inventors: **Damon Schell**, Long Beach, CA (US); **William R. Yex**, Redondo Beach, CA (US); **Benjamin R. Davidson**, Torrance, CA (US)

(73) Assignee: **HONDA MOTOR CO., LTD.**, Tokyo (JP)

(**) Term: **15 Years**

(21) Appl. No.: **29/653,859**

(22) Filed: **Jun. 19, 2018**

(51) LOC (12) Cl. **12-08**

(52) U.S. Cl.

USPC **D12/91**

(58) **Field of Classification Search**

USPC D12/86, 90-92; D21/424, 433, 434, 533; 296/181.1-181.5, 183.1

CPC B62D 25/00; B62D 25/06; B62D 33/00; B62D 35/00

(57) **CLAIM**

The ornamental design for a vehicle body and/or replica, as shown and described.

DESCRIPTION

FIG. 1 is a left, front perspective view of a vehicle body and/or replica showing our new design;

FIG. 2 is a left, rear perspective view thereof;

FIG. 3 is a right, front perspective view thereof;

FIG. 4 is a right, rear perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The broken lines shown in the figures are included for the purpose of illustrating portions of the vehicle body and/or replica and form no part of the claimed design.

1 Claim, 10 Drawing Sheets
